UNITED STATES PATENT OFFICE.

PETER CARNEY, OF NEW YORK, N. Y., ASSIGNOR TO THE J. L. MOTT IRON WORKS, OF SAME PLACE.

CISTERNS FOR WATER-CLOSETS.

SPECIFICATION forming part of Letters Patent No. 320,625, dated June 23, 1885.

Application filed March 12, 1885. (No model.)

To all whom it may concern:

Be it known that I, PETER CARNEY, of the city, county, and State of New York, have invented a new and useful Improvement in Cisterns for Water-Closets, of which the following is a specification.

My invention is designed as an improvement upon the device secured by Letters Patent No. 292,160, granted January 22, 1884, and relates, essentially, to a cistern operated by the seat of the water-closet both when the seat is depressed and when released; and the object of my invention is to give a preliminary flush to the closet when the seat is depressed, and an after flush when the seat is released and rises.

In the drawings, Figure 1 is a plan of the cistern. Fig. 2 is a vertical section, at x x of Fig. 1, through the shell of the cistern, the valves and other parts being in elevation; and Fig. 3 is a detached section through the preliminary-flushing valve, and Fig. 4 is a section longitudinally of the trunk between the two compartments without the valve or its movable seat.

The cistern is a box, preferably of cast-iron, with two compartments, A B, and having sides a a , ends b b , and bottom c cast in one piece. The dam d and trunk e are also cast with the rest of the cistern. Said trunk e is in the compartment A, and runs along above the bottom in one of the angles between one of the sides a and the bottom b , and this trunk opens at the end through the dam d into the compartment B.

A ring is fitted into an opening cast in the top of this trunk, the same forming a seat for the valve f , and this valve f has a guide, 2, a rubber ring, a bail, 3, and a rod, 4, connecting said valve to the lever g . This lever g is pivoted at 5 within the cistern, and its outer end is connected by a chain or wire, 6, to the seat of the closet, or to a platform or the door of the closet, and the other end of said lever is provided with the weight g' .

The water is allowed to run into the compartment A by the ball-valve h , and when the valve f is open the water passes through the trunk and into the compartment B.

The parts of the cistern shown in Fig. 2 are

in the position they assume after the closet-seat is released and during the flushing operation.

The valve i is around the lower end of the overflow-pipe k , as is usual in cisterns of this character, and the top of the pipe k is connected by a rod, k' , to an eye upon the lever g , and this valve, in Fig. 2, is shown open for the water to run by pipe l to the closet.

The preliminary flush for the closet is given by the valve m , which has an internal rubber washer, m' , and the lever n is hinged by lugs 7 to the valve m . Said lever n is pivoted at 8 to lugs cast upon the bottom c of the cistern. The lever n is bent with an offset at 10, and the float o has a screw-stem, o' , passing through the offset 10, and the position of the float may be varied by said screw-stem and the screw be clamped by nuts 11, if desired.

The pipe l' leads from the seat of this valve m to the pipe l . When the compartment B is emptying, (see Fig. 2,) the ball o falls and the lever n opens the valve m , and the water then flows from both pipes l l' until the compartment B and trunk are empty.

When the closet is used and the seat depressed, the lever g is pulled down, and the valve i closed and the valve f opened. The water then flows from the compartment A through the trunk e into the compartment B, and because the valve m is open a portion of this water flows away by the pipe l' , and gives a preliminary flushing of the closet. More water enters the compartment B than can pass away by the valve m . Consequently the water rises in this compartment, and soon lifts the float o and closes the valve m , and the preliminary flushing ceases. The water then finds its level in the compartments A and B, and additional water is admitted by the ball-valve h .

When the closet-seat is released and the weight g' returns the parts to their normal position, the valve f is closed, the valve i is opened, and the closet is flushed by the contents of the compartment B flowing through the pipe l to the closet, and the float o descends, opening the valve m .

I claim as my invention—

1. The combination, with a cistern for water-closets having a partition and the trunk e

opening through the same, of the weighted lever *g*, pipe *l*, and valves *f* and *i*, and a valve, *m*, and its lever and float within the compartment B, and a pipe, *l'*, from the valve *m* to the pipe *l*, whereby a preliminary flushing is given to the closet when the lever *g* is operated, substantially as set forth.

2. The combination, with the water-closet cistern, of a valve to supply water into the cistern, a pipe to allow a preliminary wash to pass to the closet, a float and valve to close

the same by the accumulation of the water, and a lever and valve and pipe to discharge the water from the cistern to the closet, substantially as specified.

Signed by me this 4th day of March, A. D. 1885.

PETER CARNEY.
